[57] CLAIM

The ornamental design for a refrigerated display case, substantially as shown and described.

DESCRIPTION

FIG. 1 is a front elevational view of a refrigerated display case showing my new design;

FIG. 2 is a top plan view;

FIG. 3 is a right side elevational view; and

FIG. 4 is a perspective view.

The back of the refrigerated display case of the present invention is plain and unornamented.

FIG. 2

FIG. 1

FIG. 3

FIG. 4
